VOLTAGE REGULATOR

Bryant D. Lund, 1955 Hollywood Ave.,
Salt Lake City, Utah 84108

Filed May 16, 1968, Ser. No. 11,975

Term of patent 14 years

Int. Cl. D13—03

U.S. Cl. D26—1

FIG. 1

FIG. 3

FIG. 2

FIG. 4

FIGURE 1 is an elevation view of the voltage regulator, the side opposite that shown having a flat and unornamented surface.

FIGURE 2 is a top view of the housing, the side opposite that shown having a flat and unornamented surface.

FIGURE 3 is a right end view of the voltage regulator shown in FIGURE 1.

FIGURE 4 is a left end view of the voltage regulator shown in FIGURE 1.

I claim:

The ornamental design for a voltage regulator, as shown and described.
